H. SNODGRASS

HAIR WAVER

Filed Oct. 6 1927

UNITED STATES PATENT OFFICE.

HASCAL SNODGRASS, OF BISBEE, ARIZONA.

HAIR WAYER.

Application filed October 6, 1927. Serial No. 224,466.

This invention relates to hair wavers and more particularly to a device for imparting a permanent Marcel wave to the hair and is adapted for waving the hair on one side of the head at a single operation and so efficiently performing the function that the hair will remain in what is known as a permanent wave for a considerable length of time.

A further object is to provide a device of this character which can be easily operated without danger of burning the patient and which will most efficiently perform the functions intended.

With these and other objects in view, the invention consists in certain novel features of construction and combinations and arrangements of parts, which will be more fully hereinafter described and pointed out in the claims.

20 In the accompanying drawings—

Figure 1 is a plan view of my improved device;

Figure 2 is an end view of Figure 1;

Figure 3 is an enlarged view in section on 25 the line 3—3 of Figure 1;

Figure 4 is a view in section on the line 4—4 of Figure 3, the iron being shown in elevation.

My improved device comprises what I shall term a base member 1 and a series of heating elements which I shall term irons 2. The base member 1 has an arm 3 fixed to one end and adjustably connected to an upright or support 4 by means of a bolt 5 and a nut 6 to permit of adjustment to support the device as desired with relation to the head of the patient.

The base member 1 comprises a series of receptacles 7 of general U-shape in cross section and extending from end to end of the base. These receptacles 7 may be formed in the base in any way desired and, as a matter of fact, constitute parallel grooves, and I preferably locate in the base member between the receptacles 7 heating elements 8 with a casing of asbestos or other non-conducting material 9 extending around the lower face of the base member and preventing any transmission of heat from the base member to the outside.

The heating elements 8 are merely shown more or less diagrammatically as it is of course to be understood that these elements may take any form and are of the type in which electricity may be employed to generate heat.

The series of irons 2 are hingedly connected, as shown at 10, to bifurcated brackets 11 on one end of the base member 1, and they are adapted to be positioned in the several receptacles 7 and have a cross sectional shape and a surface contour conforming to the shape and contour of the receptacles 7 but are smaller in cross section than are the receptacles, so that when all the irons are in position a sinuous passage or space is provided for the accommodation of hair 12, and felt or other coverings 13.

Furthermore, it will be noted that these irons are of such a size that they fit together at their outer portions so as to prevent the escape of heat and are made to accommodate electric heating elements 14, the terminals 15 of which project through insulated extensions 16 on one end of the base member 1.

The opposite end of the base member 1 is provided with a series of U-shaped spring clips 17 having flared upper ends to receive handles 18 on the irons and insulated from the irons. These clips 17 act as catches to maintain the irons in proper position in the base member but permit the irons to be swung on their pivots, as indicated in dot and dash lines in Figure 4.

The operation of my improved device is as follows:

The irons 2 are all swung out of operative position relative to the base member 1, the sheet of felt or other material 13 is positioned against the walls of the receptacles 7 and may be moistened with any suitable material. The hair 12 is then placed on the sheet 13 and the series of irons 2 are then brought into proper operative position to the base member, these irons being moved in position in regular succession so as to exert pressure on the hair without undue strain. The irons of course are held in operative position by the clips 17 and the hair is left in the device as long as necessary to give the desired permanent Marcel wave.

The broad idea of the invention is to provide a base member, preferably heated, and a plurality of pivoted irons, also heated, which are adapted to move into and out of operative relation to the base member, and I provide a sinuous space for the accommodation of hair and covering material therefor to curl the hair due to the heat of the parts, and while I have illustrated what I believe to be a preferred embodiment of my invention it is obvious various changes and altera-

tions might be made in the general form of the parts described without departing from the invention and hence I do not limit myself to the precise details set forth but consider myself at liberty to make such changes and alterations as fairly fall within the spirit and scope of the appended claims.

I claim:

1. A hair waver, including a base member, 10 a plurality of irons hingedly connected at one end to the base member and removably connected at their other ends to the base member, said base member and irons forming a sinuous passage for the accommodation 15 of hair to heat and curl the same, electric heating elements in the irons, and heating elements in the base.
2. A hair curler, including a base member having a series of parallel U-shaped receptacles, heating elements in the base member between the U-shaped receptacles, an iron for each receptacle hingedly connected at one 20 end to the base member and removably con-

nected at its other end to the base member, 25 said irons also of general U-shape externally but smaller than the receptacles, heat elements in said irons, and said irons of a width to fit close together when in the receptacles.

3. A hair curler, including a base member having a series of parallel U-shaped receptacles, 30 an iron for each receptacle hingedly connected at one end to the base member and removably connected at its other end to the base member, said irons also of general U-shape externally but smaller than the receptacles, 35 heat elements in said irons, and said irons of a width to fit close together when in the receptacles, a sheet of insulating material secured to the face of the base member, and heat elements within the base member between the receptacles. 40

Signed at Bisbee in the county of Cochise and State of Arizona this 27th day of Sept., A. D. 1927.

HASCAL SNODGRASS.
